UNITED STATES PATENT OFFICE.

ROBERT FRICKE, OF WAIPAHU, TERRITORY OF HAWAII, ASSIGNOR OF ONE-FOURTH
TO ERNEST W. GREENE, OF WAIPAHU, OAHU, AND ONE-FOURTH TO WILLIAM G.
HALL, OF HONOLULU, TERRITORY OF HAWAII.

CANE CAR.

Application filed October 5, 1925. Serial No. 60,629.

The invention relates to improvements in cars for transporting sugar cane and the like and has for its object to provide a car of the platform type having end walls and completely open sides with flexible longitudinal members extending between and around the upper portions of the end walls and preferably constituting a flexible band having releasable couplings adjacent the end walls, which band is supported in its adjusted position by guide studs on the end walls, the longitudinal reaches or sections of the band extending along the sides of the car being connected at intervals by pendant flexible loops, the lower portions of which engage the platform of the car and are preferably anchored thereto by pins, so as to retain the loops in proper relation when the car is being loaded.

20 The invention is illustrated in the accompanying drawings, in which:—

Fig. 1 is a side elevation of a car involving the novel construction.

Fig. 2 is an end elevation of the car body.

25 Fig. 3 is a half plan of the latter.

Referring to the drawings, 1 indicates the platform of a car of the general type employed for transporting sugar cane, or like materials or commodities, from the harvest fields to the mill or other place of disposition, said car being provided with the usual end walls comprising corner posts 2 and cross planking 3. As a matter of convenience and to facilitate the loading of 30 bundles of cane, each end wall is provided with a middle post 2', which is connected at its upper end with the upper ends of the corner posts by inclined L beams 2''.

Extending between and around the end walls near the top thereof is a flexible band or loop 4 provided at points adjacent the end walls with detachable clips or fastening devices 7, said member 4 constituting the longitudinal elements of the side retaining 45 means for the load. As indicated, the member 4 is held in position by means of studs 5 on the outer lateral faces of the corner posts and studs 6 on the end faces of the corner posts, said studs preferably being 50 provided with rollers to guide the flexible member 4, which passes over the studs 5 and under the studs 6, as indicated more particularly in Figs. 1 and 2.

Connected to the longitudinal reaches of

the flexible band 4 and disposed at intervals longitudinally of the car are loops 10, which depend from the closed loop 4 with their bottom sections extending transversely of the platform and in contact therewith, the mid section of each loop being detachably anchored to the platform by a pin 11, the several pins being set in the platform and serving to prevent displacement of the transverse loops during the loading operation.

Preferably the flexible upper longitudinal loop, which is continuous, and also the transverse loops are formed of chains, although it will be understood that any other suitable strand-like material, such as rope, wire, or wire cable, may be employed, provided the ends of the transverse loops are securely fastened to the longitudinal reaches of the upper continuous loop to preserve the desired spaced relation of the transverse loops longitudinally of the car body.

As thus constituted, the longitudinal continuous loop 4 and the parallel series of transverse loops 10 form strong, durable and flexible side walls for the car, which will retain the large and heavy bundles of cane loaded onto the car by the usual loading machines, permitting the car to be loaded to capacity without danger of rupturing or impairing any portion of the car.

This arrangement of the flexible retaining means also facilitates the unloading of the cane from the cars directly onto the carriers at the mill by attaching a suitable hoisting mechanism to the reach of the chain on the side opposite the carrier and casting loose the shackles or detachable connectors 7 adjacent the end walls of the car, which permits the chains or flexible connectors on the side of the car adjacent the carrier to drop down beside the car, so that, when the hoisting mechanism raises the opposite side of the chain structure, the load will be discharged directly onto the carrier.

When all of the cane has been discharged, the upper member 4 is again looped around the studs 5 on the end walls, the free ends of said member united by the shackles 7 and the mid sections of the transverse loops 10 engaged with the pins 11 on the top of the platform, so that the car is then ready to receive another load.

What I claim is:

1. A car for transporting sugar cane and

the like having end walls and open sides above the platform, longitudinal flexible members extending between and around the upper portions of the end walls and having releasable couplings adjacent the end walls, and spaced transverse flexible members connected at their ends to said longitudinal members and forming pendant loops the lower portions of which overlie the platform.

10 2. A car for transporting sugar cane and the like having end walls and open sides above the platform, longitudinal flexible members extending between and around the upper portions of the end walls and having 15 releasable couplings adjacent the end walls, spaced transverse flexible members connected at their ends to said longitudinal members and forming pendant loops the lower portions of which overlie the platform, and 20 means for anchoring the overlying portions to the platform.

3. A car for transporting sugar cane and the like having end walls and open sides above the platform, longitudinal chains extending between and around the upper portions of the end walls and having releasable 25 couplings adjacent the end walls, and spaced transverse chains connected at their ends to said longitudinal chains and forming pendant loops the lower portions of which overlie the platform.

4. A car for transporting sugar cane and the like having end walls and open sides above the platform, longitudinal chains extending between and around the upper portions of the end walls and having releasable 35 couplings adjacent the end walls, spaced transverse chains connected at their ends to said longitudinal chains and forming pendant loops the lower portions of which overlie the platform, and pins in the platform for anchoring the lower portions of the loops.

5. A car for transporting sugar cane and the like having end walls and open sides

above the platform, longitudinal flexible 45 members extending between and around the upper portions of the end walls and having releasable couplings adjacent the end walls, guide studs on the edges and outer faces of the end walls to retain said longitudinal 50 members in position, and spaced transverse flexible members connected at their ends to said longitudinal members and forming pendant loops the lower portions of which overlie the platform.

6. A car for transporting sugar cane and the like having end walls and open sides above the platform, longitudinal chains extending between and around the upper portions of the end walls and having releasable 60 couplings adjacent the end walls, guide studs on the edges and outer faces of the end walls to retain said longitudinal chains in position, and spaced transverse chains connected at their inner ends to said longitudinal chains 65 and forming pendant loops, the lower portions of which overlie the platform.

7. A platform car having end walls, a flexible band looped between and around the upper portions of the end walls, releasable 70 couplings in said band adjacent the end walls, and spaced pendant flexible loops connected at their ends to the longitudinal reaches of the flexible band with their lower portions overlying the platform.

8. A platform car having end walls, a flexible band looped between and around the upper portions of the end walls, releasable 80 couplings in said band adjacent the end walls, guide studs on the edges and outer faces of the end walls to retain the flexible band in stretched relation, and spaced pendant flexible loops connected at their ends to the longitudinal reaches of the flexible band with their lower portions overlying the plat- 85 form.

In testimony whereof I affix my signature.

ROBERT FRICKE.
